OIL WELL PUMPING APPARATUS

David M. Hammett, Tulsa, Okla.

Application December 7, 1934, Serial No. 756,495

3 Claims. (Cl. 103—1)

My invention relates to new and useful improvements in oil well pumping apparatus, and has for its objects; to provide a means and method of forcing the fluid in the well to the surface 5 whereby less power is required to pump the fluid, the efficiency of the pump is increased, and less strain is placed upon the sucker rods; without impairing the safety of the equipment used.

Heretofore, the fluid has been raised either in 10 the tubing or in the casing, but not in both tubing and casing as with my invention, and in the practice of my invention the fluid is caused to travel thru both tubing and casing with the results hereinafter mentioned, and at the same 15 time.

With the above and other objects in view which will be disclosed as the description proceeds, my invention consists in the novel features hereinafter set forth, shown in the accompanying 20 drawing, and more particularly pointed out in the appended claims.

Referring to the drawing in which like numerals represent similar parts throughout the several views:

25 Fig. 1 is a view in cross section of a string of pipe in a well, and a conventional casing head on said pipe, and also showing in side elevation a string of tubing therein carrying a packer and a pump, and a string of sucker rods in said tubing, 30 together with other conventional well apparatus.

Fig. 2 is a view in cross section of the well head shown in Fig. 1, but with a pipe leading from the casing to the flow line.

1 represents a conventional string of casing in 35 a well, 2 a string of tubing therein and with said tubing having apertures 3 near the bottom thereof and also apertures 4 near the top thereof, and with said casing carrying a conventional casing head 5 with a tubing support 6 and a stuffing box

40 7 thru which a conventional string of sucker rods 8 is run to a conventional pump or working barrel 9 which is attached to said tubing 2 thru a conventional packer 10 on the end of said tubing. A customary lead line 11 runs from said tubing 45 to the flow tanks which are not shown. The outlets 12 of the casing head are closed, forming a partition across the head of the casing. The packer seals off and forms a partition between casing and tubing. The pump is submerged or

50 partially submerged in the liquid to be pumped, which said liquid is indicated by broken lines 13. A conventional gas anchor 14 may be attached to the bottom end of the pump. A pipe 15 may, if desired, be connected into the casinghead thru 55 one of the outlets 12 therefrom and into the flow

line 11, thus permitting the fluid to flow directly from the casing to the flow line.

In operation, sucker rods 8 are reciprocated in the usual manner to operate pump 9, with a result that the fluid being thereby raised passes thru the packer 10 and into the tubing 2, and is free to then flow either up within said tubing or out of the tubing thru apertures 3 and into the casing 1 at a point above the packer and also above the pump or pump valves, and in the latter 10 instance may travel upwardly thru both the tubing and the casing until the top of the well is reached, whereupon that portion of the fluid which may be traveling thru the tubing continues 15 to travel therein until it empties into the lead line 15 11, and that part of the fluid which may be traveling in the casing and outside of the tubing re-enters the tubing thru the apertures 4 in said tubing and commingles with the fluid in said tubing and flows therefrom into said flow line or lead 20 line 11 the same as does that portion of the fluid 20 which may have traveled up within said tubing.

It is obvious that packer 10 and the closed casing head 5 provides a seal for that portion of the casing which lies between them. It is also 25 obvious that the pump 9 may be placed on the tubing 2 above the packer 10. It is further obvious that the apertures 3 and 4 must be positioned in tubing 2 at points above both the valves of the pump and the partition formed by the packer and below the partition formed by the casing head; that is, the apertures must be intermediate of 30 said casing head on the one hand and said pump and packer on the other. Furthermore it is obvious that instead of flowing the fluid out of the 35 tubing into the flow line, the same results could be accomplished by closing, or leaving open, said flow line or lead line 11 and connecting said line into the casing head 5 thru one of its outlets 12.

The result is that the fluid being pumped has 40 a freer and more unrestricted flow than it would have if confined to a travel in the tubing alone and that the slippage or load loss is not as great because of the larger cross sectional area of the travel, and that as a consequence less power is 45 required to lift the load and less strain is placed on the string of sucker rods with a further result that not only are said rods less subject to breakage but also less subject to elongation or stretch under the load. Moreover the pressure within 50 and without the tubing is equalized and the tubing is not caused to be stretched or elongated as in the case of its conventional manner of use. As a further consequence of the lessening of the stretching 55 of the rods and of the tubing under pumping, 55

less loss of stroke in the pump results, and with more travel of the pump plunger in the pump, greater pumping efficiency is secured. The total result is the accomplishment of the objects of the invention as heretofore set forth. The same result may of course be effected by connecting a branch line from one of the casing head openings 12 to the lead line 11, either with or without the apertures 4 in the tubing, or by closing the lead line 11 from the tubing 2 and retaining apertures 4 in said tubing and connecting the lead line 11 directly in to one of the openings 12 of the casing head 5, it being immaterial how the fluid outlet from the tubing and casing is effected, for with my invention the tubing may serve only as a support for the packer 10 and pump 9 and as a guide for the sucker rods 8, permitting the fluid to flow upwardly in the casing along the lines of least resistance and unimpeded except for the wall of the casing, the tubing and the string of sucker rods which may or may not have thereon the conventional sucker rod guides which prevent the sucker rods from rubbing on and wearing the tubing.

Having thus fully disclosed my invention, what I claim and desire to secure by Letters Patent is:

1. In an oil well, the combination of a string of casing, a string of tubing therein, a partition between said casing and said tubing at the upper end of said casing, a partition between said casing and said tubing at the lower end of said tubing,

an outlet for the passage of fluid from said tubing into said casing and situate intermediate of said partitions, an upper outlet from said casing, a pump connected into the lower end of said tubing, and a string of sucker rods passing thru said tubing and operatively connected with said pump. 5

2. In an oil well, the combination of a string of casing, a string of tubing therein, a partition between said casing and said tubing at the upper end of said casing, a partition between said casing 10 and said tubing at the lower end of said tubing, an aperture in said tubing at the lower end thereof and above said last named partition, another aperture in said tubing at the upper end thereof and below said first named partition, a pump connected into the lower end of said tubing, and a string of sucker rods passing thru said tubing and operatively connected with said pump. 15

3. In an oil well, the combination of a string of casing, a string of tubing therein, a partition 20 between said casing and said tubing at the upper end thereof, a partition between said casing and said tubing at the lower end of said tubing, an outlet for the passage of fluid from said tubing at the lower end thereof and above said last 25 named partition, an outlet from said casing and tubing at the top end thereof, a pump connected into the lower end of said tubing, and a string of sucker rods passing thru said tubing and operatively connected with said pump. 30
